(57) **CLAIM**

We claim the ornamental design for an agitator assembly, substantially as shown.

DESCRIPTION

FIG. 1 is a perspective view of the agitator assembly.

FIG. 2 is a front elevational view thereof.

FIG. 3 is a side elevational view thereof.

FIG. 4 is a side elevational view taken from the opposite side of FIG. 1.

FIG. 5 is a rear elevational view thereof.

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
